US00D683141S

(12) United States Design Patent
Symons

(10) Patent No.: US D683,141 S
(45) Date of Patent: * May 28, 2013

(54) UNIVERSAL STAND

(71) Applicant: Dominic Symons, Wilkie Edge (SG)

(72) Inventor: Dominic Symons, Wilkie Edge (SG)

(73) Assignee: Bluelounge Pte. Ltd., Wilkie Edge (SG)

() Term: 14 Years

(21) Appl. No.: 29/441,435

(22) Filed: Jan. 4, 2013

(51) LOC (9) Cl. 06-07

(52) U.S. Cl.

USPC D6/310; D14/447

(58) Field of Classification Search

USPC D6/310, 312, 311, 406.3, 491, 419, 460, 451; D14/447, 448, 451, 432, 439, 440, D14/457, 460, 461, 239, 250, 251, 253, 217, D14/238.1, 229, 375; D3/218; 248/917-924, 248/688, 441.1, 451, 454, 460, 463, 136, 248/149, 150, 164, 166, 17, 6.2; 361/679.22, 361/379.26, 679.09
